UNITED STATES PATENT OFFICE

148,107

DESIGN FOR A CAMERA TRIPOD HEAD

Russell Katz, Hamilton, Ohio, assignor to Paul Benninghofen and Eleanor C. Diesbach, both of Hamilton, Ohio, trustees

Application September 25, 1946, Serial No. 133,554

Term of patent 14 years

(Cl. D61—1)

To all whom it may concern:

Be it known that I, Russell Katz, a citizen of the United States, residing at Hamilton, in the county of Butler and State of Ohio, have invented a new, original, and ornamental Design for a Camera Tripod Head, of which the following is a specification, reference being had to the accompanying drawing, forming a part thereof.

Figure 1 is a perspective view of the camera tripod head showing my new design.

Figure 2 is a side view thereof.

Figure 3 is a view taken on a right angle to Figure 2 further illustrating the design.

I claim:

The ornamental design for a camera tripod head, substantially as shown.

RUSSELL KATZ.
